DESIGN FOR A CASING FOR FLUSHING APPARATUS

Martin W. Thompson, Hammond, Ind.

Application October 20, 1941, Serial No. 103,824

Term of patent 7 years

To all whom it may concern:

Be it known that I, Martin W. Thompson, a citizen of the United States, residing at Hammond, in the county of Lake and State of Indiana, have invented a new, original, and ornamental Design for a Casing for Flushing Apparatus, of which the following is a specification, reference being had to the accompanying drawing, forming a part thereof.

Figure 1 is a front elevational view of a casing for flushing apparatus showing my new design; Fig. 2 is a side elevational view; Fig. 3 is a rear elevational view; and Fig. 4 is a top plan view.

I claim:

The ornamental design for a casing for flushing apparatus, as shown.

MARTIN W. THOMPSON,
